HEATED SHOE PRESS PAD

Michael A. Turski, Buffalo, N. Y.

Application January 23, 1941, Serial No. 375,629

1 Claim. (Cl. 219—19)

This invention relates to devices for use in connection with the manufacture or repair of cemented type leather or textile shoes, or the like, and more particularly to an improved form of pad for supporting, for example, a shoe sole during pressing and gluing of a lasted shoe against the sole.

One of the objects of the invention is to provide an improved shoe part supporting pad of the self heating type wherein an improved form of heating element is incorporated to provide advantages in connection with the maintenance and repair thereof. Other objects and advantages will appear from the specification hereinafter.

In connection with the manufacture or repair of cemented type shoes it is a present practice to support, for example, the sole part upon a resilient pad while pressing the lasted shoe part against the sole until such time as the cement providing the connection therebetween has become thoroughly set. For this purpose it is also the present practice to heat the sole supporting pad by some suitable medium such as by circulating a hot liquid through the interior of the pad or by mounting an electrical resistance heating element within the body of the pad, so as to elevate the temperature of the pad during the pressing operation in order to shorten the time required to provide complete setting of the cement. The present invention relates more specifically to an improved form of supporting pad incorporating the electrical resistance type of heating element, whereby the heating element may be readily withdrawn from the body of the pad and replaced whenever necessary, in an improved manner.

In the drawing:

Fig. 1 is a plan of a heating pad of the invention, with a portion broken away to show the interior thereof; and

Fig. 2 is a side elevation thereof.

The drawing exemplifies the invention as comprising a pad member 10 formed of rubber composition material or the like, which is generally shaped in plan view similar to the shape of a shoe sole. The upper face of the pad 10 is dished as at 12 to complement the naturally curving shape of the shoe sole to be supported by the pad.

The pad heating means of the invention comprises a generally U shaped conduit 14 embedded within the body of the pad member 10 in such manner as to lie adjacent the upper face thereof and so as to be contiguous to the side edges thereof. Thus, the conduit 14 lies approximately

below the cemented joint to be procured between the edges of the lasted shoe and the sole piece. An electrical resistance element 16 in the form of a wire of any suitable metallic alloy substance is provided with a covering 18 of asbestos or the like, and the insulated element 16 is threaded through the conduit 14 as illustrated by the drawing. The ends of the resistance element are arranged to extend beyond the corresponding ends of the conduit 14 for connection to suitable electrical conductors (not shown) which in turn connect to a suitable source of electrical energy, as will be understood by those skilled in the art. Thus, the shoe pad is adapted to be heated, as required, by transmission of electrical current through the resistance wire 16 to hasten the setting of the cement of the cementing operation.

Thus, the specific arrangement of the heating element wire 16 within the conduit 14 provides means whereby the heating element wire may be readily threaded through the conduit as required to repair the wire element whenever the latter becomes burned out or broken or otherwise incapable of continuing in operation. In such event the damaged heating element is simply withdrawn from the conduit by pulling upon its exposed ends, and a new heating element may be installed by threading it endwise through the conduit into the operative position shown in Fig. 1. Thus, the heating element of the device may be replaced as required without disturbing the mounting of the conduit within the pad 10, and it is no longer necessary to discard the pad member simply because the heating element becomes damaged and unworkable. Consequently, the use of my improved shoe press pad provides improved economies and advantages not found in press pads of the prior art.

Although only one form of the invention has been shown and described in detail, it will be apparent to those skilled in the art that the invention is not so limited but that various changes may be made therein without departing from the spirit of the invention or the scope of the appended claim.

What is claimed is:

A shoe sole part press pad for use in the operation of pressing together cemented shoe sole and upper parts, said pad comprising a body of resilient material having a dished upper surface of shoe sole-like planform adapted to support thereon a shoe sole part for pressing the latter into cemented relation against another shoe part, a conduit member of relatively rigid material fixedly embedded within said pad body and so ar-

ranged as to lie substantially parallel to the plan-form periphery of said pad to provide a smoothly curving generally U-shaped open passageway through the body of said pad from points of entry and exit therefrom at the heel end of said pad, said conduit being also arranged to be disposed substantially equidistant throughout its extent from said upper surface of said pad while being spaced at all points throughout slightly inwardly of the body of said pad, and a flexible electrically insulated heating element of metal in the form of a wire freely slidable within said con-

duit and inserted therein to extend therethrough and to terminate exteriorly of said pad for connection to an electrical power source and to provide a continuous electrical circuit through said pad, said conduit and said insulated wire being so relatively dimensioned that said wire is freely withdrawable from said conduit so as to be replaceable by sliding insertion of a similar substitute wire into said conduit by feeding the substitute wire with an endwise motion into said conduit until it is threaded therethrough.
